UNITED STATES PATENT OFFICE.

PHILIP GORDON BROWN, OF DULUTH, MINNESOTA.

ROBE-LOCK.

1,129,378.

Specification of Letters Patent. Patented Feb. 23, 1915.

Application filed December 2, 1914. Serial No. 875,160.

To all whom it may concern:

Be it known that I, PHILIP GORDON BROWN, a citizen of the United States, residing at Duluth, in the county of St. Louis 5 and State of Minnesota, have invented a new and useful Robe-Lock, of which the following is a specification.

The present invention appertains to a robe lock adapted particularly for use as an automobile accessory and designed to hold or 10 clamp the robes or garments in a secure manner, to prevent the theft thereof.

This invention contemplates the provision of a robe lock of unique construction and 15 having means for clamping or gripping the robes or garments and also having key-controlled means for opening and closing the clamp or holder.

It is also within the scope of the invention 20 to provide a robe lock of comparatively simple, inexpensive, compact and non-encumbering construction, which will be fool-proof, which may be readily and conveniently applied to an automobile body so as 25 to be associated with the robe rail or rack, and which will be convenient, efficient and practical in its use.

With the foregoing and other objects in view which will appear as the description 30 proceeds, the invention resides in the combination and arrangement of parts and in the details of construction hereinafter described and claimed, it being understood that changes in the precise embodiment of the 35 invention herein disclosed can be made within the scope of what is claimed without departing from the spirit of the invention.

The invention is illustrated in its preferred embodiment in the accompanying 40 drawing, wherein:

Figure 1 is a side elevation of the robe lock as applied below the robe rail and in the act of holding or gripping the robe or garment. Fig. 2 is a longitudinal central 45 section of the lock. Fig. 3 is a rear view of the lock, with the back plate or disk removed. Fig. 4 is a cross sectional view taken on the line 4-4 of Fig. 2. Fig. 5 is a front view of the lock. Fig. 6 is an elevation of the key for the lock, in folded condition. Fig. 7 is a longitudinal sectional view of the key in unfolded position, parts 50 broken away.

The present appliance or attachment embodies a case 1 of cylindrical or other suitable contour, and having outstanding ears 55

or lugs 2 at its rear end for attaching the same to the body B of an automobile, or to any other suitable support to which the device is to be applied. The other or forward 60 end of the case 1 is provided with a tongue-shaped jaw 3 projecting radially or at right angles therefrom, there being a reinforcing or bracing web 4 between the jaw 3 and the case 1. The case 1 and aforesaid parts carried thereby are preferably in the form of a unitary casting, although they may be constructed in various manners.

The case 1 is provided with a longitudinal circular bore 5 extending therethrough and 70 a featherway 5^a, with an enlarged circular socket or recess 6 at the inner or rear end of the bore 5, and with a still larger circular recess or depression 7 next outside the socket or recess 6.

A tongue-shaped movable jaw 8 co-operates with or complements the fixed or stationary jaw 3, and is provided at its basal or butt portion with a perpendicularly extending shank 9 fitting slidably within the 80 circular bore 5 of the case, and having a feather 9^a working in the featherway 5^a, to enable the jaw 8 to move to and from the jaw 3, without the liability of the movable jaw rotating or oscillating. The adjacent 85 faces of the jaws 3 and 8 are preferably lined or covered with rubber or similar facings or linings 9' which provide effective means for engaging the robes or garments, without the liability of injuring or cutting them.

The shank 9 of the movable jaw 8 is provided with a longitudinally circular bore 10 extending through the basal portion of the jaw 8 to the outer side thereof, the inner or rear end of the bore 10 being provided 95 with a screw-threaded portion 11, the threads of which are of the square type.

A screw 12 having square screw threads, is threaded through the threaded portion 11 of the bore 10, and is provided with an outwardly or forwardly projecting stem 13 projecting within the bore 10 of the shank 9 and jaw 8 carried thereby. A collar 14 is provided upon the stem 13 of the screw 12, adjacent the free or outer end of the stem 100 13, and fits snugly within the bore 10, the outer or protruding portion 15 of the stem 13 being squared or otherwise formed for the engagement of the key. The collar 14 serves three functions, namely, it serves to 105 hold the stem 13 of the screw 12 properly in place within the bore 10, it limits the in-

sertion of the key upon the stem 13, and it limits the movement of the jaw 8 away from the jaw 3, since a shoulder 15^a of the bore 10 formed by the screw threaded portion 11 will contact with the collar 14 before the screw threaded portion 11 of the movable jaw disengages the screw 12.

The inner or rear end of the screw 12 is provided with a finger or stub 16 engaged through a circular slotted plate or washer 17 seated snugly within the recess or socket 6, and a retaining collar 18 is provided upon the protruding or free end of the finger or stub 16 and bears or seats against the washer 15 or disk 17 to prevent the outward or forward movement of the screw 12, but to enable the screw to rotate readily. The washer 17 is radially slotted at 17^a to facilitate the assembling of the parts of the lock.

20 by engaging the same laterally with the neck formed by the stem of the screw between the end of the latter and the collar 18.

A back plate or disk 19 is fitted snugly and secured within the recess or depression 7 to close the rear or inner end of the case 1.

25 The plate or disk 19 holds the screw 12 in place against rearward or inward movement.

In applying the robe lock to an automobile body B, as suggested in Fig. 1, the case 1 is preferably secured to the automobile body immediately below the robe rail or rack R with the jaws 3 and 8 projecting properly, so that when the robe or garment 30 G is thrown or placed over the rail R, it may be introduced or inserted between the jaws of the lock to be gripped and securely held therebetween, to prevent the robe or garment being stolen.

35 It will be noted that the case or element which supports the stationary jaw is provided with the means for attachment to the vehicle, whereby the space within the vehicle, occupied by the lock when at its robe-engaging or closed adjustment is minimized, and the key seat or operating end of the jaw-adjusting element, consisting of the screw, is accessible at the front or outer face of the movable jaw, and also, that the 40 screw serves to both forcibly move the jaw, to compress the interposed portion of the robe, and to lock or hold said jaw in its adjusted position.

The lock L is operated or controlled 45 through the medium of a key K which as illustrated embodies a handle 20 having a key shank 21 pivoted therein, the free end of the key shank 21 having a socket bit 22 engageable over the squared or protruding 50 end 15 of the screw stem 13. The key handle 20 is provided with a recess 23 into which the shank 21 is swingable, to enable the key to be compactly folded, so as to be readily carried in the pocket, and whereby 55 the shank 21 may be swung outwardly, as

seen in Fig. 7, to enable the key to be employed for opening or closing the jaws of the lock.

The jaws of the lock are opened and closed by inserting the key into the mouth 70 or outer end of the bore 10 so as to engage the screw stem 13, and then by rotating the key in one direction or the other, the jaws may be separated or moved toward one another, as desired, to either release or 75 clamp the robe, garment, or other article. It will be noted that when the screw 12, which is held against longitudinal movement within the case, is rotated, it will cause the shank 9 of the jaw 8 to travel longitudinally in one direction or the other, according to the direction in which the screw is rotated, and whereby the jaw 8 will be moved correspondingly.

The working parts of the present device 85 are concealed or housed so as to prevent tampering therewith, it being noted that the squared or key-engaging portion 15 of the screw stem 13 is housed and protected within the bore 10 of the jaw 8 and its 90 shank 9, so that the screw cannot be actuated without the use of a suitable or proper key. It is evident that the key-engaging portions of the key and screw stem may be altered in various manners, to afford a number of key changes, in order that special 95 keys may be required for the locks when put on the market.

The present lock provides a serviceable and valuable accessory for an automobile, 100 for securely holding the robes and garments to prevent the theft thereof, while the occupant or occupants of the automobile or motor car are absent. The other advantages and capabilities of the present invention 105 will be obvious to those versed in the art, it is thought, without further comment being deemed necessary.

Having thus described the invention, what is claimed is:—

1. A vehicle robe lock, adapted for location below a robe-rail and having an inner or rear stationary jaw member provided with means for attachment to a vehicle body, an outer or front movable jaw member 115 mounted on the stationary jaw member and movable horizontally from front to rear thereof, and jaw-adjusting and holding means, having a key-seat accessible at the outer or front face of the movable jaw.

2. A vehicle-robe lock having a stationary jaw member including a tubular case for attachment to a vehicle body, the bore of the case terminating at its rear or inner end in a recess, a movable jaw member having a 125 tubular shank slidably mounted in the bore of the case, and means for operating the movable jaw member including a screw, threaded in the bore of the tubular shank, having a key-seat at its outer or front end 130

and having a reduced neck at its inner or rear end, and a radially slotted detachable plate engaged with said neck and seated in the recess of the case.

- 5 3. A vehicle robe lock having a stationary jaw member provided with a tubular case, attachable to a vehicle body, a movable jaw having a tubular shank mounted in said case, a feed screw swiveled in the case at its rear 10 or inner end, threaded in the shank of the movable jaw member, and having a key-seat at its front or outer end, a collar carried

by the feed screw and fitting in the bore of the tubular shank, and a stop shoulder in the bore of the shank for coöperation with 15 the collar.

In testimony that I claim the foregoing as my own, I have hereto affixed my signature in the presence of two witnesses.

PHILIP GORDON BROWN.
